UNITED STATES PATENT OFFICE.

FRANZ X. WAGNER, OF NEW YORK, N. Y., ASSIGNOR TO UNDERWOOD TYPEWRITER COMPANY, OF NEW YORK, N. Y., A CORPORATION OF NEW JERSEY.

UNIVERSAL-BAR MECHANISM FOR TYPE-WRITERS OR LIKE MACHINES.

SPECIFICATION forming part of Letters Patent No. 763,528, dated June 28, 1904.

Application filed April 28, 1903. Serial No. 154,696. (No model.)

To all whom it may concern:

Be it known that I, FRANZ X. WAGNER, a citizen of the United States, and a resident of the borough of Manhattan, city, county, 5 and State of New York, have invented certain new and useful Improvements in Universal-Bar Mechanism for Type-Writers or Like Machines, of which the following is a specification.

10 My invention relates to type-writers, and has particular reference to a novel construction of the universal-bar mechanism and its operation controlled by the key-levers of the machine and its connections for operating the 15 escapement.

I will now describe a type-writer embodying my improvements and will then point out the novel features of my invention in the appended claims.

20 Reference is to be had to the accompanying drawings, in which—

Figure 1 is a sectional elevation of a type-writer, taken from front to rear at about the center of the machine. Fig. 2 is a sectional 25 elevation taken substantially on line 2 2 of Fig. 1. Fig. 3 is a plan with parts in section approximately in the plane indicated by the line 3 3 in Fig. 1. Fig. 4 is a rear view of the machine with parts omitted and some 30 parts in section on line 4 4 of Fig. 1. Fig. 5 is a detail rear elevation of the universal bar and the parts directly connected therewith, and Fig. 6 is a plan of the same parts with portions broken away.

35 As shown best in Fig. 1, I mount upon the frame A of the machine key-levers, such as B, having keys, such as B', and pivoted at B². Each lever is connected with an elbow-lever C, fulcrumed at C', the connection, as indicated at C², being in the nature of a pin-and-slot 40 connection. The upper end of each elbow-lever is operatively connected with the impression mechanism. For instance, a type-bar D is provided for each elbow-lever, such 45 type-bar being fulcrumed at D' upon the segment A' and having a pin-and-slot connection

D² with the corresponding elbow-lever C. So far the construction is substantially the one usually employed in the Underwood type-writer.

Each of the elbow-levers C is provided with a rearwardly-extending toe C³, arranged adjacent to the pivot C' and adapted to engage the bottom surface of a universal bar E', which is carried by two arms E, connected at 50 their rear ends by a sleeve E², which is pivotally mounted upon a stationary rod e. By reference to Figs. 1 and 3, and particularly to the latter, it will be seen that the toes C³ of the several elbow-levers C vary in length, the toes 55 being shortest at the center and increasing in length toward both sides. The pin-and-slot connections C² also vary, as indicated in Fig. 3, their distance from the pivot C' increasing from the center of the machine toward the 60 sides. This variation in the position of the connection between the key-lever and the elbow-lever is not in itself here claimed as my invention. The universal bar is normally kept down by means of a spring H, which at 65 one end is attached to a bracket A² and at the other end is engaged with a pressure-lever G, pivoted at G' and engaging an arm F, which is rigidly secured to the sleeve E². The upper arm of the pressure-lever G may be provided with a series of notches G², so that the action of the spring may be graduated. The end of the arm F is so formed that the distance between the pivot and the point of contact of the pressure-lever G with the arm F will increase as the arm F moves up, thereby gradually increasing the effect of the spring H. The arms E have upward extensions E⁶, connected at the top by a horizontal cross-bar E⁷, which carries a frame E⁸, which may be termed a 80 "dog-carrier."

Upon the frame E⁸ are mounted the fixed dog K and the loose dog K'. The latter is normally in engagement with the rack N' of the carriage N and is pivotally supported upon 85 a pin L, which forms part of or is secured to the frame E⁸. The loose dog K' is thus capa-

ble of moving up and down, and to normally keep said dog in its upper position I provide a spring K^7 , attached at one end to the frame E^3 and at the other end to an arm K^5 , rigidly connected with the dog K' . The said dog is secured to a dog-arm K^3 , which not only swings on the pivot L , but is further capable of a longitudinal sliding movement on the said pin to the extent of a letter-space, this movement being governed by the length of a slot K^2 , through which the said pin projects. Preferably the dog-arm K^3 consists of two sections adjustably connected, as indicated at K^4 , so that the normal position of the dog K' may be brought into proper relation to the normal position of the dog K . It will be understood that the depression of a key-lever causes the universal bar to move upward and swings the dog-carrier E^3 to the rear, so as to bring the fixed dog K into engagement with the carriage-rack N' and to release the loose dog K' from said rack. As soon as released the loose dog is moved lengthwise of the rack by its spring K^7 , a projection E^8 of the dog-carrier limiting the upward movement of said dog. When the type-lever is released, the universal bar is returned to its first position by the spring H , and the loose dog is again brought into engagement with the carriage-rack and the spring which propels the carriage causes the latter to be fed, the spring K^7 being much weaker than the carriage-driving spring. In this manner the feed of the carriage is obtained. When the carriage is moved by hand toward the right—that is, toward left when looking at the machine from the rear, as in Fig. 4—the spring K^7 will yield to allow the loose dog to slip over the teeth of the rack N' .

In many machines a tabulating device is employed, which comprises mechanism for temporarily releasing the carriage from the feed-dog. This tabulating device may be of the well-known character in which a rock-shaft M' , extending lengthwise of the carriage, is employed, the said rock-shaft being provided with an arm M , which projects over a toe K^6 of the dog-arm K^3 . It will be understood that when the tabulator is operated the arm M swings downward, so as to withdraw the loose dog K' from engagement with the carriage-rack N' , and thus release the carriage.

I desire to call particular attention to the varying length of the toes C^3 , as shown best in Fig. 3. It will be seen that the toes are progressively longer as the distance between the pivot C' and the pin-and-slot connection C^2 increases. In this manner I am enabled to secure an absolutely uniform movement of the universal bar whichever key-lever is depressed notwithstanding the varying distance between the pivot C' and the pin-and-slot connection C^2 . Another feature which is of importance in my invention is the construction of the universal bar and the arms E^6 and their

connecting-bar E^7 as a rigid unitary member, 65 which in practice may be cast in one piece together with the sleeve E^2 , which connects the arms E at their rear ends.

By the improved construction hereinbefore described a very light touch is obtained and 70 at the same time great simplicity and accessibility of the main parts of the device.

The drawings show a ribbon-guide and a ribbon-feed mechanism which I have not further described herein, as such parts form the 75 subject-matter of another application for patent filed by me on September 22, 1903, Serial No. 174,163.

What I claim as new, and desire to secure by Letters Patent, is—

1. In a type-writer or like machine, the combination with key-levers, type-bars, and elbow-levers connecting the key-levers with the type-bars, the point of connection of the elbow-levers with the corresponding key-levers varying for the different key-levers, and the said elbow-levers being provided with toes which increase in length as the distance increases between the pivot of the elbow-levers and their point of connection with the corresponding 90 key-levers, of a universal bar arranged to be engaged by the said toes, and escapement mechanism controlled by the movement of said universal bar.

2. In a type-writer or other machine, the combination with key-levers, type-bars, an intermediate mechanism for transmitting motion from the key-levers to the type-bars, the connection of said intermediate mechanism with the key-levers varying with different 100 key-levers, and each of these intermediate mechanisms being provided with a toe, the length of these toes varying correspondingly to the variation in the connection of the key-levers with said intermediate mechanism, of 105 a universal bar adapted to be engaged by said toes, and escapement mechanism controlled by the movement of the universal bar.

3. In a type-writer or other machine, the combination with key-levers, type-bars, and elbow-levers connecting said key-levers and type-bars and provided with rearwardly-extending toes, of a universal-bar frame adapted to be engaged by said toes, an escapement mechanism, one member of which is carried 110 by said frame directly, and a pressure-lever engaging said frame.

4. In a type-writer or other machine, key-levers and a universal-bar frame both pivoted at the rear of the machine, type-bars, elbow-levers connecting said key-levers with said type-bars and provided with toes to engage the universal-bar frame, escapement mechanism controlled by the movement of said frame, and a pressure-lever arranged to engage said 120 frame and disposed forwardly of the pivot of such frame but rearwardly of the elbow-lever pivots.

5. In a type-writer or other machine, the combination, with key mechanism, of a universal-bar frame operated by said mechanism, escapement mechanism having a connection 5 with said frame so as to be controlled by the movement thereof, and a pressure-lever entirely separate from said connection and engaging the universal-bar frame.
6. In a type-writer or other machine, a frame mounted to oscillate about a horizontal axis, an escapement member carried by said frame and movable thereon toward and from the axis of oscillation, a carriage provided 15 with a mating escapement member, a rock-shaft the axis of which is parallel to that about which said first-named escapement member oscillates with its carrying-frame, an arm on the rock-shaft for moving the escapement member on said frame out of engage-

ment with the companion member on the carriage, so as to release the carriage, without moving said frame, and key-operated mechanism for swinging said frame. 20

7. In a type-writer or other machine, the combination, with key mechanism, of a universal-bar frame operated by said mechanism, escapement mechanism, one member of which is carried by said frame, a pressure-lever having a shifting engagement with said frame, and a spring adjustably connected with said 25 lever. 30

In testimony whereof I have signed my name to this specification in the presence of two subscribing witnesses.

FRANZ X. WAGNER.
